DESIGN FOR AN AIR FILTER

Melroy Sinclair, Maplewood, Mo.

Application September 25, 1939, Serial No. 87,374

Term of patent 14 years

To all whom it may concern:

Be it known that I, Melroy Sinclair, a citizen of the United States, residing in Maplewood, St. Louis County, State of Missouri, have invented a new, original, and ornamental Design for an Air Filter, of which the following is a specification, reference being had to the accompanying drawing, forming part thereof, in which:

Fig. 1 is a front elevational view of an air filter incorporating my novel design; and

Fig. 2 is an end elevational view of the air filter.

I claim:

The ornamental design for an air filter, as shown.

MELROY SINCLAIR.
